UNITED STATES PATENT OFFICE.

ELBERT O. HASKINS, OF RUTHERFORD, NEW JERSEY, ASSIGNOR TO
ABENDROTH BROS., OF PORT CHESTER, NEW YORK, A CORPORA-
TION OF NEW YORK.

HINGE AND CATCH PLATE FOR BOILERS AND FURNACES.

No. 825,722.

Specification of Letters Patent.

Patented July 10, 1906.

Application filed August 21, 1905. Serial No. 275,059.

To all whom it may concern:

Be it known that I, ELBERT O. HASKINS, a citizen of the United States, residing at Rutherford, in the county of Bergen and State of New Jersey, have invented an Improvement in Hinge and Catch Plates for Boilers and Furnaces, of which the following is a specification.

Heretofore the cast-metal bodies or sections of steam and hot-water boilers and hot-air furnaces have been made with integral hinge and catch plates, and as these projected from the plane of the outer surface they were very liable to be broken off in transportation. Where these parts were broken off, resort was had to drilling and tapping the cast-metal shell to secure a plate upon the surface; and the object of my invention is to remove the possibility of such inconvenience.

In carrying out my invention the cast frame or section of the boiler or furnace at the opening to receive a door is thickened at predetermined places, which are provided with dovetail slots from the edges inward, forming recesses in the surface of the metal open to the edges of the door-aperture. The hinge or catch plates agree in dimensions with the longitudinal and cross-sectional configurations of such slots, and they are adapted to be received therein and driven or forced to place. Each of these plates carries a lug formed therewith, either with a hole for the hinge-pin or as a catch for the latch or nosing of the door.

In the drawings, Figure 1 is an elevation of a section at one end of a steam or hot-water boiler for the purpose of illustrating the application of my invention. Fig. 2 is a perspective view at the left-hand side of a door-opening, showing a perspective view of the hinge-plates. Fig. 3 is a perspective view at the right-hand side of a door-opening. Fig. 4 is a perspective view of the catch-plate. Fig. 5 is a sectional plan longitudinally of a hinge-plate, while Fig. 6 is an elevation of a hinge-plate alone.

a represents a part of or the whole of one section of a boiler or furnace provided with door-apertures *b*. These door-apertures may be at the ends of flues which pass through the upper parts of the several sec-

tions going to make up the boiler or furnace, and they may represent the entrance for coal to the combustion-chamber or the opening for the removal of ashes from the boiler or furnace, it being a fact that my invention is applicable to a steam or hot-water boiler or to a hot-air furnace wherein a section or shell is made of cast metal.

In forming these parts of cast metal I provide thickened portions *a'* or, in other words, parts at either one or both sides of a door-aperture that are thickened, both longitudinally and vertically, at *a'*, and these parts are provided with dovetail slots from the edges inward opening in the surface of the metal, wherein the same form recesses open to the edges of the door-aperture. This is plainly shown in Fig. 3.

I provide hinge and catch plates *c c'* of a shape to fit the dovetail slots, the outer surface of said plates being narrower than the rear or back surface and the top and bottom edges diverging or spreading from the width of the surface or face to the width of the back. Each of these plates is formed with a lug, the lug *d* of the hinge-plate *c* being provided with a hole for the hinge-pin of the door and the catch-plate *c'* provided with a lug *d'* in the form of a catch for the latch or nosing of the door.

While the hinge and catch plates are respectively in the said dovetail slots, it is the purpose of my invention to ship from the place of manufacture to the place of sale and destination the sections or shell of a steam or hot-water boiler or hot-air furnace with said hinge and catch plates separate, and after the furnace or boiler is set up then to place the hinge or catch plates in position for use. In this way risk of breakage is reduced to a minimum, and as the parts are interchangeable there is no necessity of fitting these plates to place in the factory. After the boiler or furnace is set up and the hinge or catch plates placed in the grooves and driven home to position for use the said parts quickly rust together, so that it is substantially impossible to remove them and they become to all intents and purposes for use an integral structure.

In one part of the drawings I have shown a

2

door e with hinges e' and a latch e^2 , the other portion of the figure showing only the door-openings.

I claim as my invention—

- 5 1. The combination with the cast-metal body or section of a steam or hot-water boiler or hot-air furnace having slots formed in the cast metal of the body from the edges of the door-openings inward, of hinge and catch plates adapted to be received in and interlocking with said slots and having lugs formed upon the outer surface thereof for the hinge and catch of the door.
- 10 2. The combination with the cast-metal body or section of a steam or hot-water boiler or hot-air furnace having thickened walls at predetermined places and at said places provided with dovetail slots from the edges inward forming recesses in the surface of the metal opening to the edges of the door-aperture, of hinge and catch plates which agree in dimensions with the longitudinal and cross-sectional configurations of such slots so that they are wider across their rear surface than across their outer surface and adapted to be received therein, and lugs formed with and upon the outer surface of said hinge and catch plates provided with holes for the hinge-pin or as a catch for the latch or nosing of the door.
- 15 3. The combination with the cast-metal body or section of a steam or hot-water boiler or hot-air furnace having walls thickened both vertically and horizontally on the inner surface and at predetermined places and at said places provided with dovetail slots from the edges inward forming recesses in the surface of the metal opening to the edges of the door-aperture, of hinge and catch plates which agree in dimensions with the longitudinal and cross-sectional configurations of such slots so that they are wider across their rear surface than across their outer surface and adapted to be received therein, and lugs formed with and upon the outer surface of said hinge and catch plates provided with holes for the hinge-pin or as a catch for the latch or nosing of the door.
- 20 4. The combination with the cast-metal body or section of a steam or hot-water boiler or hot-air furnace having thickened walls at predetermined places and at said places provided with dovetail slots from the edges inward forming recesses in the surface of the metal opening to the edges of the door-aperture, of hinge and catch plates which agree in dimensions with the longitudinal and cross-sectional configurations of such slots and adapted to be received therein, and lugs formed upon the outer surface of said hinge and catch plates provided with holes for the hinge-pin or as a catch for the latch or nosing of the door.
- 25 5. The combination with the cast-metal body or section of a steam or hot-water boiler or hot-air furnace having thickened walls at predetermined places and at said places provided with dovetail slots from the edges inward forming recesses in the surface of the metal opening to the edges of the door-aperture, of hinge and catch plates which agree in dimensions with the longitudinal and cross-sectional configurations of such slots and adapted to be received therein, and lugs formed upon the outer surface of said hinge and catch plates provided with holes for the hinge-pin or as a catch for the latch or nosing of the door.

hinge-pin or as a catch for the latch or nosing of the door.

3. The combination with the cast-metal body or section of a steam or hot-water boiler or hot-air furnace having walls thickened both vertically and horizontally on the inner surface and at predetermined places and at said places provided with dovetail slots from the edges inward forming recesses in the surface of the metal opening to the edges of the door-aperture, of hinge and catch plates which agree in dimensions with the longitudinal and cross-sectional configurations of such slots so that they are wider across their rear surface than across their outer surface and adapted to be received therein, and lugs formed with and upon the outer surface of said hinge and catch plates provided with holes for the hinge-pin or as a catch for the latch or nosing of the door.

Signed by me this 15th day of August, 1905.

ELBERT O. HASKINS.
